UNITED STATES PATENT OFFICE.

ALEX LAUGHLIN, OF SEWICKLEY, PENNSYLVANIA.

HEATING-FURNACE.

SPECIFICATION forming part of Letters Patent No. 643,143, dated February 13, 1900.

Application filed May 22, 1899. Serial No. 717,723. (No model.)

To all whom it may concern:

Be it known that I, ALEX LAUGHLIN, a citizen of the United States, residing at Sewickley, in the county of Allegheny and State of Pennsylvania, have invented or discovered certain new and useful Improvements in Heating-Furnaces, of which improvements the following is a specification.

The invention described herein relates to certain improvements in continuous heating-furnaces generally; but the improvements are more especially adapted for use in connection with that class or kind of continuous heating-furnace from which the billet is automatically discharged.

The invention is hereinafter more fully described and claimed.

In the accompanying drawings, forming a part of this specification, Figure 1 is a sectional elevation of a portion of a furnace adjacent to the billet-discharge opening having my improvements applied thereto. Fig. 2 is a sectional plan view of the same. Figs. 3 and 4 are views similar, respectively, to Figs. 1 and 2, illustrating a modification of my improvement.

In the practice of my invention the furnace is constructed, as regards the hearth, the means for shifting the billets along the furnace, and supporting them during such movement, substantially as described and shown in Letters Patent No. 599,182, granted February 15, 1898, to myself and Josef Reuleaux. As set forth in said patent, the billets are shifted along the supporting-rails 3 into an opening formed across the bottom of the furnace at or near its point of highest heat. A conveyer 8 is located below the bottom of the furnace in line with the discharge-opening, so that billets passing through such opening will drop onto the conveyer and be moved thereby to a reducing-mill. In order to prevent the entrance of cold air into the furnace through the discharge-opening, swinging doors have been arranged in such position as to close the opening. These doors are provided with counterweights adapted to hold the doors in closed position, but permit their swinging when a billet drops thereon for the passage of the billet onto the conveyer. It has been found that the billets seldom drop on the doors so as to force both of them down equally.

As a result of this unequal movement of the doors the billet is deflected by the door having the greater movement to such an extent 55 that it drops on one end of the conveyer-rolls or misses the same entirely. In order to insure the dropping of the billets in the desired position on the conveyer-rolls, only one door, 9, is employed for closing the discharge-opening. 60 This door, which is made of sufficient width to extend across the opening, is hinged to the bottom plate of the furnace at one side of the opening. As the door swings down under the weight of the billet the latter will 65 slide off the free edge of the door and strike against the vertical plate 10, which is secured, preferably, to the frame of the conveyer, so as to be approximately tangential to the arc described by the free edge of the door. It is 70 preferred to make the face of the plate slightly convex, so that the billet will be deflected toward the median line of the conveyer. The door may be formed with trunnions 11 projecting from its ends in line with 75 its rear edge, as shown in Figs. 1 and 2, said trunnions being mounted in bearings formed on or attached to the side plates of the furnace. Weights 12 are adjustably mounted on the arms 13, which are so attached to the 80 trunnions that the weights will hold the door yieldingly in closed position. It is preferred to construct the door so that water or other cooling fluid may circulate therethrough, the passage or passages in the door being connected with axial passages in the trunnions, 85 through which the cooling fluid is introduced by suitable inlet and outlet pipes.

As shown in Figs. 3 and 4, the door and bottom plate may be formed with intercalating knuckles, through which suitable pins are passed, and, if desired, the counter-balancing-weights may be connected to the front or free edge of the door by chains 14, passing over guide-pulleys 15. The passages 95 in the door may be connected to a suitable source of supply by a section of hose or other suitable flexible connection.

It is preferred to form a rib or projection 16 on the bottom plate of the furnace around the discharge-opening, said ribs being provided with passages for the circulation of a cooling medium. The ends of the pipes forming the billet-supporting rails 3 have their

ends curved or bent so as to support the billets as they move into the discharge-opening. The ends of these pipes project down through the bottom plate and are held in position by 5 nuts or other suitable means.

I claim herein as my invention—

A continuous heating-furnace provided with a discharge-opening formed through its bottom, in combination with a door hinged to 10 one side of the discharge-opening, automatic means for normally closing the door, a con-

veyer arranged to receive the billets and a stationary guide-plate arranged parallel to the conveyer and adapted to direct the billets into the conveyer as they pass through said 15 opening, substantially as set forth.

In testimony whereof I have hereunto set my hand.

ALEX LAUGHLIN.
